UNITED STATES PATENT OFFICE.

NATHAN E. TYRRELL, OF KANSAS CITY, MISSOURI.

VALVE CONTROL.

Application filed April 21, 1924. Serial No. 707,931.

To all whom it may concern:

Be it known that I, NATHAN E. TYRRELL, a citizen of the United States, and a resident of Kansas City, county of Jackson, State of Missouri, have invented a certain new and useful Improvement in Valve Controls, of which the following is a complete specification.

This invention relates to valve control means and is more particularly adapted for use in controlling oil burners; where it is desirable to provide inexpensive remote control equipment by which the customary feed valve may be accurately adjusted to meet variations of out door temperature without the necessity of going to the basement, where the heating plants are usually located.

Another object is to provide variable stop mechanism to limit the opening and closing movements of the valve and thus provide maximum and minimum rates of fluid supply and consequently regulate the size of the flame.

A still further object is to provide means by which the valve may be positively locked in its closed position to guard against the accidental flooding of the furnace, due to the opening of the valve by unauthorized persons.

With the objects named in view the invention consists in certain novel and useful features of construction and organization of parts as hereinafter described and claimed; and in order that it may be fully understood, reference is to be had to the accompanying drawing, in which:

Figure 1 is a side elevation of a valve and operating mechanism constituting the invention in operative relation thereto.

Figure 2 is a section similar to Figure 1, but at right angles thereto.

Figure 3 is a top plan view of the remote control dial.

Figure 4 is a top plan view of the ordinary operating handle of the valve and the dial and stop mechanism carried thereby.

Figure 5 is a side view of the valve with the operating mechanism in vertical section.

In the said drawing, where like reference characters identify corresponding parts in all of the figures, 1 represents any suitable sort of valve for controlling communication between the fuel line 2 and the burner feed line 3. This needle valve has a stem 4 projecting beyond its casing and is formed with a squared portion for the reception of an

operating handle 5 equipped with a stop and indicating finger 6, hereinafter more particularly described. The valve stem terminates beyond the handle 5 in a reduced extension portion 7.

Slipped over the valve stem below the handle 5 is a circular plate 8 having a downwardly extending bifurcated portion 9 of sufficient length to embrace the burner supply line 3 of the valve and hold the disk in fixed position as regards rotation and also supports the disk in position. The disk is strengthened as at 10 throughout a portion of its periphery, and formed in said strengthened portion are a plurality of equi-spaced holes 11 between which are any suitable indicating numbers 12 with which the finger 6 of the operating handle is adapted to register in order to indicate the relative position of the valve.

Upon the installation of the valve and mechanism, the operator will determine the maximum degree of opening movement which should be allowed the valve to correspond with the lowest average temperature of the district. A fixed stop pin 13 will then be inserted in one of the holes 11 to limit the opening of the valve to this maximum point, said pin being so located that the finger 6 of the operating handle 5 will abut the same. Provision is thus made to guard against the accidental opening of the valve to an excessive degree and, perhaps, the flooding of the burner and the consequent wasting of oil.

It is also desirable to provide means for limiting the closing movement of the valve so that it will be impossible for the operator to accidentally limit the supply of oil to such a degree as to lead to the extinguishment of the flame of the burner. In order to accomplish this result and still make it possible for the operator to entirely cut off the flow of oil, without the use of tools, the person installing the burner will determine the least quantity of oil which can be consumed without extinguishing the burner and will then insert in the corresponding hole a stop pin 14 held yieldingly elevated in the path of the finger 6, by means of an expansion spring 15. When it is desired to entirely shut off the valve to the flow of oil, the operator depresses the stop 14 thus withdrawing it from position 110 and permitting the stop and indicating finger 6 to pass above the same and the valve

consequently turned to closed position, as indicated in dotted lines in Figure 4.

In order to prevent the opening of the valve by the remote control means, hereinabove described, after it has been turned to closed position and the burner consequently extinguished, a dog 16 is pivotally mounted on the upper end of the stop 14, and is adapted to be swung to the dotted line position shown in Figure 4 into contact with the base of the finger 6, and thus effectively guards against the slightest opening movement of the valve. It will be apparent that when it is desired to open the valve, 15 the operator must manually rotate the dog 16 to its inoperative position.

As it is sometimes desirable to regulate the size of the flame by means of a remote control in an upstairs room for example the reduced end 7 of the valve stem is received within the bore of a coupling 17 and is held fixedly in position by means of a set screw 18. Received in the opposite end of the coupling, is the end of an extension rod 19 held in position by a second set screw 20. The upper end of the rod preferably passes through an opening 21 in the floor 22 of one of the rooms of the building and has a bearing in an opening formed in an inverted strap bridge member 23 projecting downwardly into the opening 21. The bridge member forms a part of an indicating disk 24 provided with indicating numerals 25 arranged in a manner similar to the numbers of the plate 8 and coincidental therewith, and said disk is held in position by means of suitable screws 26 or the like, in engagement with the floor 22. It will be evident that, if desired, the 30 disk 24 may be located on a bracket or the like projecting from one of the walls of the room instead of being mounted on the floor.

If the device is mounted in the floor, the 45 top of the rod 19 will be cut off flush with the top of the floor, and said rod will be flattened slightly as at 27 on one of its sides for engagement with a similar shaped opening formed in a tubular key member 50 28 having a combined operating and indicating finger 29 for registering with the indicating numbers of the plate or disk 24. In this connection it will be apparent that due to the flattening of the rod at one of its sides, it will be necessary that the key 55 shall always be applied in the same position so that it may properly register with the indicating characters.

The rod is cut off flush with the face of 60 the disk, so that no protruding surface to break the plane of the floor shall be formed. By having a removable key, the likelihood that children will tamper with the setting of the valve is obviated. It will be evident 65 that by forming the upper bearing for the

rod in the shape of an inverted strap arch, a pair of openings 23^a are provided at opposite sides of the rod, through which dirt and refuse accidentally swept into the device will be free to fall to the floor of the 70 cellar and will not clog or interfere with the proper operation of the remote control.

By the use of the control pins or stops above described, it will be apparent that a 75 safe working range for the operation of the burner is provided and that the accidental extinguishment of the flame or the flooding of the burner by the use of the remote control are obviated.

From the above description it will be apparent that I have produced a device of the character described which possesses all the features of advantage set forth as desirable; and while I have described and claimed the 85 preferred embodiment of the same, I reserve the right to make all changes properly falling within the spirit and scope of the appended claims.

I claim:

1. In an apparatus of the character described, a valve, a plurality of corresponding dials, one of which is adapted to fit the stem of the valve and the other being secured in a remote position, variable stop means for limiting the movement of said valve stem, a rod adapted to pass through the remote dial and form a rigid connection with said valve stem, and means for turning the rod at the remote dial.

2. In an apparatus of the character described, a valve, a dial adapted to fit the stem of the valve, means for holding the dial in fixed position, variable stop means for limiting the movement of said valve stem, a corresponding dial secured in a remote position, a rod passing through the remote dial and forming a rigid connection with said valve stem, indicating means on the remote dial, and means for turning the rod at the remote dial.

3. In an apparatus of the character described, a valve, a plurality of corresponding dials, one being adapted to fit the stem of the valve in fixed position, a remote dial in fixed position, a rod passing through the remote dial and forming a rigid connection with said valve stem, and means for turning the rod at the remote dial.

4. In an apparatus of the character described, a valve, a marked dial axially aligned with the stem of the valve and provided with an extension engaging the valve to fix the position of the dial, a second dial having markings corresponding to the marks of the first dial, a rod secured to the valve stem and engaging the second dial, and an indicator for engagement with the rod to turn the same with reference to the marks on the second dial.

5. In apparatus of the character described, a valve, a rod coupled at its lower end to the stem of the valve, a dial secured to a floor and provided with a depending bridge engaging an opening in the floor and forming a journal for the upper end of the rod, and an indicator for extending radially of the valve and provided with a hub extending through the dial above the bridge, the hub and rod having detachable but rigid relation as regards turning movement.
- 10 6. In apparatus of the character described, a valve having an indicating arm attached to the valve stem, a dial, and a stop pin normally in the path of travel of said indicating arm, said pin being yieldingly-actuated to permit said arm to pass beyond the pin.
- 15 7. In a device of the character described, a valve having an indicating arm attached
- to the valve stem, a dial, a fixed pin in the path of travel of said indicating arm for limiting the opening movement of the valve, and a second pin in the path of travel of said indicating arm to limit the closing movement of the valve, said second pin being yieldingly-actuated to permit the indicating arm to pass beyond the pin.
- 20 8. In an apparatus of the character described, a valve having an indicating arm attached to the valve stem, a dial, a pin in the path of travel of said indicating arm to limit the closing movement of the valve, said second pin being yieldingly-actuated to permit the indicating arm to pass beyond the pin to closed position, and a latch for holding the valve in closed position.

In witness whereof I hereunto affix my signature.

NATHAN E. TYRRELL.
